US00D805066S

(12) **United States Design Patent** (10) **Patent No.:** **US D805,066 S**
Leabman (45) **Date of Patent:** **** Dec. 12, 2017**

(54) **LAPTOP COMPUTER WITH ANTENNA**(71) Applicant: **Energous Corporation**, San Jose, CA (US)(72) Inventor: **Michael A. Leabman**, Pleasanton, CA (US)(73) Assignee: **Energous Corporation**, San Jose, CA (US)(**) Term: **14 Years**(21) Appl. No.: **29/487,645**(22) Filed: **Apr. 10, 2014**(51) **LOC (10) Cl.** ..... **14-02**(52) **U.S. Cl.**USPC ..... **D14/315**; D14/318; D14/327(58) **Field of Classification Search**

USPC ..... D14/138, 230-238, 299, 358, 318; D12/42, 43; 343/700 MS, 700 R-705, 343/711-713, 735, 736, 741, 748, 767, 343/795, 819, 840, 846, 866, 871-908; 455/90.2, 90.3, 91, 128, 269, 344, 347, 455/562.1

CLAIM

The ornamental design for a laptop computer with antenna, as shown and described.

DESCRIPTION

FIG. 1 is a front perspective view of a laptop computer with antenna;

FIG. 2 is a front view of the laptop computer with antenna; FIG. 3 is rear view of the laptop computer with antenna; FIG. 4 is a right side view of the laptop computer with antenna; and,

FIG. 5 is a left side view of the laptop computer with antenna.

The broken lines in the figures depict portions of the laptop computer with antenna that form no part of the claimed design.

1 Claim, 4 Drawing Sheets# US D805,066 S
